(57) **CLAIM**

I claim the ornamental design for a machine for manufacturing cigarettes, as shown and described.

DESCRIPTION

FIG. 1 is a front-top-right side perspective view of machine for manufacturing cigarettes, showing my new design; FIG. 2 is a front-top-left side perspective view thereof; FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof; and,

FIG. 8 is a rear elevation view thereof.

The broken lines in the drawings depict portions of the machine for manufacturing cigarettes that form no part of the claimed design.

1 Claim, 4 Drawing Sheets
